UNITED STATES PATENT OFFICE

FLORENCE L. LE VQUE, OF LOS ANGELES, CALIFORNIA

DESIGN FOR WOMAN'S SOCK

Application filed August 4, 1928. Serial No. 27,700. Term of patent 7 years.

To all whom it may concern:

Be it known that I, FLORENCE L. LE VQUE, a citizen of the United States, and a resident of Los Angeles, Los Angeles County, California, have invented a new, original, and ornamental Design for Women's Socks, of which the following is a specification, reference being had to the accompanying drawings, forming a part thereof.

In the drawings

The figure is a perspective view of a sock constituting the design. The dotted line showing represents the opposite edge of the cuff at the bottom and the outline of the upper edge of the sock beneath the cuff.

I claim:

The ornamental design for woman's sock, substantially as shown and described.

FLORENCE L. LE VQUE.
